DELAWARE.

WALL BOARD.

Application filed October 2, 1925. Serial No. 60,029.

This invention relates to a method for constructing and applying fibre, plaster, pulp and other types of boards having a paper or other fibrous surface, and especially types 5 suited for walls, ceilings, and building construction.

The invention embraces a new method for concealing joints, nails or other fasteners used in applying such boards, so that the 10 wall or other surface made therefrom shall have a continuous surface of the material which forms the surface of the board. The invention also includes the product.

The principal objects of my invention are 15 to provide a simple and efficient means of concealing joints, nails or other fasteners, in wall boards of the paper lined type, to eliminate the necessity of using any putty or filler which would form a non-homogeneous surface, and to enable a wall or ceiling 20 to be built of wall boards without the necessity of having any panelling or projecting strips of other covering, thus making the finished wall or ceiling look as smooth as a wall 25 built of lath and plaster.

This invention is applicable to fiber boards, as well as boards made of other materials, and especially relates to such boards when applied to building construction to replace 30 lath and plaster.

Heretofore, when wall boards or other composition boards have been used in the construction of walls and ceilings, it has been found necessary to conceal the heads of 35 nails, and of joints between the boards, by means of strips or panelling. While putty has been used to fill such cracks and cover such fasteners, this method has been unsatisfactory, for the two different types of 40 surfaces, that is, the paper or other fibrous surfacing of the board, and the putty, are readily distinguishable when painted or cal- cined, or even when finished with a wall 45 paper. Many substitute methods have been devised but none so far has proven entirely satisfactory. My new method eliminates the 50 difficulties experienced with the methods used in the past and furnishes a continuous paper or fiber surface which effectively conceals nail heads and other fasteners, and also the joints.

All of the figures are somewhat diagrammatic in character, and show cross-sections through wall boards. Fig. 1 shows a cleav-

age plane in the outer or finishing layer or 55 liner of a wall board. Fig. 2 shows how the liner may be cut to the cleavage plane and then folded back to permit the driving of nails. In Figs. 3 and 5, the liner is cut and folded in a somewhat different manner. In 60 Fig. 4 a strip is cut from the liner and the cut-out so formed is covered with a substitute strip. Fig. 6 illustrates the joint between adjacent wall boards after the nails have been driven to secure the boards to 65 studding, but before the cut-out has been filled with the finishing material. Figs. 7, 8, 9 and 10 show different ways of filling the cut-out to cover the joint.

The invention is carried out by leaving 70 cleavage planes in the board, preferably between certain layers of the paper or other material used for liners, and parallel to the face of the liner. I define "cleavage plane" 75 for the purpose of this invention as a plane of separation between layers of paper or other fibrous materials so that the layers may be readily separated at predetermined areas. Methods for forming such planes will be described hereinafter. The zones of cleav- 80 age are located in the board at the places where the board is to be nailed or otherwise fastened to the structure, that is, these cleavage zones register with the studding or other framing to which the board is to be fastened. 85

Fig. 1 shows a portion of a cross-section of a board containing a cleavage plane made according to my invention. The central portion, 1, may be of pulp fibre, or plaster, or any other filling used in wall board construc- 90 tion. The liners 2 and 3 may be of paper or other fibrous material suitable for surfacing boards, and may vary greatly in thickness. Both liners, or either one, may have a cleavage plane, 4, for the purpose of 95 this invention.

A cleavage plane may be made by gluing two sheets of covering material together in such a way that the glue is omitted at the cleavage zone. In another method I propose to insert a thin ribbon of paper between the layers of pulp as they are being laid down by a paper machine. For example, if the covering layer or liner is a fiber board made of four layers of pulp pressed together, 100 the thin ribbon of paper may be inserted between the first and second, or the second and third layers, or between the third and 105

fourth layers of the pulp. This thin ribbon will form a cleavage zone which causes the layers of pulp to be easily separated at the zone. Other methods may be used to form 5 the cleavage zone.

The width of the cleavage zones can be made as desired, but in general they will not need to be over 2", but may vary from 1/2" to 6". The location of the cleavage 10 zones can also be varied, but in general, they should be along the edges of the boards and spaced about 16" or 24" apart, or the standard spacing of studding. The cleavage zones 15 can be indicated by markings on the surface of the liners as desired, such markings to be of such a character that they will not destroy the continuity of the surface.

When the cleavage zone is distant from the edge of the board, as in Figs. 2, 3, 4, 20 and 5, the surface of this plane is slit with a knife, or other convenient instrument, and is turned back. Such a knife should be provided with guard wings so adjusted that it will cut into the paper liner, or other fiber 25 surface, only a certain fixed depth, that is, to the cleavage plane.

Fig. 2 shows a cross-section of a board in which the finishing layer or liner has been slit to the cleavage plane and the resulting 30 flap has been turned back, exposing the cleavage zone. This exposed cleavage zone should register with the studding or other framing to which the board is to be fastened. The board is then fastened by means of 35 nails, or other fasteners, at the exposed cleavage zone, as shown in Fig. 2. The nail, or other fastener, is driven into the board far enough so that the top of it is flush with or lower than the exposed surface of the 40 cleavage plane 4. Either the underside of the flap 5 which has been turned back, or the exposed cleavage plane 4, is coated with glue or some other suitable adhesive and the flap 5 is then replaced to its original position. The nails, or other fasteners, are 45 thereby effectively concealed, and a continuous surface of the finishing layer on the wall board forms the surface of the wall or ceiling, or other structure.

Fig. 3 illustrates a modification of the 50 method shown in Fig. 2. For applying the board, the finishing layer is slit in the same manner, but the layer is peeled away from the cleavage planes on both sides of the slit 55 instead of one side as in Fig. 2.

In Fig. 4, a double slit is made in the finishing layer or liner and the strip of finishing layer so detached is entirely removed, exposing the cleavage zone. After the board 60 has been fastened, the strip so removed may be replaced, but, to secure a continuous surface, care must be taken to make the strip which has been removed register exactly 65 with its former position. If it is not desired to reuse the strip so removed, another con-

cealing strip can be substituted. A strip of paper 6, or other fibrous material of about the same character and thickness as the strip removed, but appreciably wider, is pasted or otherwise fastened, by a suitable adhesive, 70 to the cleavage plane, after the board has been fastened to the studding or other framing. As shown in Fig. 4, this strip 6 overlaps the slits on either side of the removed strip but is not pasted to the finishing layer or liner where the overlap occurs. A knife is then used to slit both this strip and the finishing layer or liner to the cleavage plane at the points A and B in Fig. 4. The trimmings thus formed from the concealing strip and the liner are removed and the concealing strip is then fastened by glue or other suitable adhesive to the cleavage plane. In this manner a continuous surface is produced due to the perfect fit of the concealing strip in the depression of the liner. 75 80 85

Fig. 5 shows the board after it has been fastened to the studding or framing, with the nails concealed by the method illustrated in Fig. 3, with the joint of the two abutting 90 papers directly above the head of the nail.

When it is desired to conceal a joint such as is caused by two boards butting against one another, as shown in Figs. 6, 7, 8, and 9, the procedure is essentially the same. 95 The cleavage zone extends back from the edge of the board a given distance, as shown. The finishing layer may either extend beyond the edge of the board or may be cut back from the edge of the board.

Fig. 6 shows a cross-section of two boards butting against each other with the finishing layer or surface of the liner cut back a certain distance from the joint and with the nails in place, the top of the heads being flush or slightly below the cleavage plane. The boards may butt tightly against one another or may be left with a space between them as illustrated in Fig. 6. If a space is left between the boards, I prefer to fill this with a suitable putty or other filler so that it will be flush with the cleavage planes. 100 105 110 115

Fig. 7 shows one method of carrying out my invention to conceal the joints. If the 115 finishing layer or liner has been cut away so that the edge is a straight line, or approximately straight, a strip of paper, or other fibrous material, of the same thickness as the finishing layer, wide enough to 120 cover the exposed cleavage zones of both boards is butted against the edge of one of the finishing layers, and is glued, or otherwise fastened by a suitable adhesive, to the exposed cleavage plane. The paper, or other fiber strip 6 overlaps but is not glued or fastened to the finishing layer which it overlaps. A slitting knife is then run down at the point B, through both the covering strip and the finishing layer underneath, and 125 130

to the cleavage plane, and the trimmed strips of finishing layer and covering strip are discarded.

The covering strip is then glued, or otherwise fastened, to the cleavage zone and forced down flush with the finishing layer.

The method of Fig. 7 may be varied as shown in Fig. 8, in which the covering strip 6 overlaps the finishing layer on both boards 10 and is trimmed and finished in the manner described for Fig. 4.

Fig. 9 shows the finished construction with the nails, or other fasteners, in place, and the joint concealed with a covering strip 15 corresponding in thickness and surface texture with the paper or other fiber used in the finishing layer of the board, thereby exposing a continuous homogeneous surface of similar material. The hairline joints at 20 the points where the finishing layer and covering strip butt together may be disregarded. They are practically invisible.

If the board has been constructed so that the finishing layer extends beyond the edge 25 of the board, as shown in Fig. 10, the method used will be similar to that for Fig. 7, except that the finishing layer is continuous and the joint which appears at the left in Fig. 7 will not be present. The method of 30 making the joint at the right will be the same as for Fig. 7.

While the illustrations show the use of nails in fastening the boards, other fasteners may be used. The cleavage zone may 35 be placed in one liner or both liners, and may be placed close to the surface or at a considerable depth below the surface of the liner as appears desirable.

Wall boards expand and contract in varying amounts with changes in temperature 40 and humidity and the joints may therefore be subject to considerable strain. Ordinary paper or other fibrous material, if used as a covering strip over the joints in walls or 45 ceilings covered with boards which have a large expansion and contraction may not expand and contract sufficiently to prevent breaking of the joint. Under these condi-

tions I have discovered that if the covering strip is creped slightly it contracts and 50 expands sufficiently to prevent such cracking. The creping can be made so slight that it cannot be readily distinguished from the smooth surface of the board, yet this is usually sufficient to compensate for the contraction and expansion of the board. 55

Throughout the specification the word "wall" has been used in its generic sense to include not only side walls but also ceilings and other like areas. 60

I claim:

1. A wall board faced with a liner having a cleavage plane, the layers of the liner being more readily separable in some portions of said cleavage plane than in other portions and being adapted to be separated in said readily separable portions to secure it to a support. 65

2. A wall board faced with a liner containing cleavage planes, the layers of the liner being more readily separable in spaced parallel zones of said cleavage plane than in other portions. 70

3. A wall board faced with a liner containing cleavage planes, the layers of the liner being more readily separable in the portion of the cleavage plane at an edge of the board and in zones running lengthwise of the board and spaced from the edges of the board than in other portions. 75

4. A board faced with a liner containing a cleavage plane, the layers of the liner being more readily separable in said cleavage plane in zones which are spaced from and parallel to each other than in other portions, the finishing layers covering the cleavage zone at an edge of the board and extending beyond said edge. 80

5. A wall board faced on both sides with a fiber liner having cleavage planes, the layers of the liner being more readily separable in some portions of said cleavage plane than in other portions. 85

In testimony whereof I affix my signature.

HOWARD F. WEISS.
